OSKAR RISCH, OF JENA, GERMANY, ASSIGNOR TO CLAY-ADAMS CO., INC., OF NEW YORK, N. Y., A CORPORATION OF NEW YORK.

HÆMACYTOMETER COUNTING CHAMBER.

Application filed August 5, 1926. Serial No. 127,461.

My invention relates to the type of microscope slides known as hæmacytometer counting chambers, which are employed for the purpose of counting blood corpuscles. 5 These counting chambers consist of a slide made of glass and provided on one of its surfaces with a fine network of lines crossing each other, to form squares, the user viewing through a microscope, a drop of 10 blood deposited on such slide or counting chamber, and effecting a count of the corpuscles within one of such squares. As made hitherto, glass slides of this type are plane or smooth on the surface opposite to 15 the network of lines, and it has been found in practice that under the microscope, the lines of such network or ruling appear white or colorless, so that it is difficult to see them and effect a proper count of the corpuscles. 20 The object of my invention is to overcome this difficulty and cause the lines of the network or ruling to stand out more prominently, or be darkened, as it were, so that they are readily visible under the microscope. 25

For this purpose, I provided any optical or other means that will produce the darkening or visibility-increasing effect above mentioned. The preferred way of carrying out 30 my invention consists in substituting, for the plane reverse surface of the slide employed hitherto, a formation that will by refraction or internal reflection cause the lines of the ruling or grating to appear dark or 35 at least more prominent than with the former construction referred to above.

Reference is to be had to the accompanying drawing, in which Fig. 1 is a face view of a hæmacytometer slide or counting chamber embodying my invention, Fig. 2 is a cross section on line 2—2 of Fig. 1, and Fig. 3 is 40 a face view of the slide or counting chamber, looking at the side opposite to that shown in Fig. 1. It will be understood that the drawing simply illustrates an example of my invention, and that other constructions may be employed without departing from the nature of my invention as set forth in the appended claims.

50 The glass body A is provided on its upper surface with one or more rulings or gratings B consisting of lines cut or otherwise produced in the said surface and crossing each other. Any of the well-known styles of

ruling may be employed. The opposite 55 (lower) surface or reverse of the body A was hitherto made smooth or plane, but in the form of my invention illustrated herein such reverse surface is provided, in registry with the rulings or gratings B, with a formation 60 which will cause a refraction or internal reflection of light such as will cause the lines of the gratings to appear more prominently than heretofore. This formation may consist, as illustrated, of concave surfaces or 65 sockets C in register with the respective gratings B and acting to produce a lense effect. These sockets are preferably produced by grinding, a cylindrical curvature (of circular arc-shape in cross-section) being indicated in Figs. 2 and 3. 70

Instead of providing the reverse surface with recesses curved after the fashion of lenses, cylindrically or otherwise, I may employ any other formation or any other device, which will cause the lines of the grating or ruling to stand out more prominently. 75 As stated at the beginning of this specification, I do not wish to restrict myself to optical means or processes for obtaining the 80 darkening or visibility-increasing effect hereinbefore explained.

It will be understood that generally a slide or counting chamber of the type herein referred to, is placed in a microscope having arrangements for throwing light against the lower surface or reverse of the slide and through such slide and the blood deposited on its upper surface. 85

I claim:

1. A hæmacytometer slide or counting chamber provided with ruling on one side and with a visibility-increasing formation on the opposite side.
2. A hæmacytometer slide or counting chamber provided with a field of ruling on one side and with a visibility-increasing refracting surface on the other side, in registry with such field. 95
3. A hæmacytometer slide or counting chamber provided with a field of ruling on one side and with a concave surface on the other side, in registry with such field, to increase the visibility of the lines of said ruling. 100

In testimony whereof I have hereunto set my hand.

OSKAR RISCH.
